(57) **CLAIM**

The ornamental design for a swingable bracket for columns for equipment for stacking and transporting piled-up and separated articles as shown and described.

DESCRIPTION

FIG. 1 is a lateral perspective view of a swingable bracket for columns for equipment for stacking and transporting piled-up and separated articles showing the new design;

FIG. 2 is a left side view thereof;

FIG. 3 is a top plan view thereof; and,

FIG. 4 is a front end view thereof.

1 Claim, 4 Drawing Sheets
